Attorney

UNITED STATES PATENT OFFICE.

WILLIAM G. BRUNS, OF SIOUX FALLS, SOUTH DAKOTA.

PUMP ATTACHMENT.

Application filed December 9, 1925. Serial No. 74,376.

This invention relates to pumping mechanism for oil and water pumps, and has more particular reference to an attachment therefore, the primary object of the invention being to provide such an attachment in order that the operating mechanism for the piston be it an electric motor, gasoline engine, or manual means, will easily raise the piston in order that the load on the up stroke 10 will be reduced and more substantially equalizing the load on the up and down stroke of the piston.

A further object is to provide an attachment of this character wherein the belt from 15 the power means to the pump operating mechanism will be prevented from slipping, which is now an existing difficulty in the operation of said pump for the reason that the up stroke requires a greater amount of 20 energy than that to which the operating mechanisms are sometimes capable.

A still further object is to provide such an attachment wherein the speed of the up and down strokes of the pump will be substantially equalized for providing a highly efficient operation of the pump and prevent jarring of the same, resulting in a longer life of the mechanism.

With the foregoing and other objects in 30 view as the nature of the invention will be better understood, the same comprises the novel form, combination and arrangement of parts hereinafter more fully described and shown in the accompanying drawings and 35 claimed.

In the drawing, wherein like reference characters indicate corresponding parts throughout both of the views:—

Figure 1 is a front elevation of a conventional pump equipped with my attachment, and

Fig. 2 is a perspective of a member of the attachment.

Now having particular reference to the 45 drawing, 5 indicates the stock of a conventional type of pump mechanism, to the upper end of which projects the usual piston rod 6 to which are connected at their upper ends the usual pitmen 7—7 through the medium of a cross arm 8 that are in turn eccentrically connected at their lower ends to spur gears 9—9 that are operatively associated with a belt pulley 10, whereby said pitmen may be effectively operated.

My invention per se, constitutes the pro-

vision of an arm 11 formed centrally with a head 12 through which extends an opening for receiving the piston rod 6, said rod being slidable through this head in a manner hereinafter more fully described.

The arm 11 is hooked at its opposite ends as at 13—13 and secured thereto at each end are relatively elongated contractile coiled springs 14—14 that are in turn secured at their lower ends to the pitmen 7—7 as 60 at 15—15.

On the down stroke of the piston rod through provision of the operating mechanism including the pitmen 7—7 the springs 14—14 will be extended whereupon at the 70 beginning of the up stroke of the piston rod said springs will serve to assist the operating mechanism in raising the pitmen 7—7 and consequently the piston rod, thus reducing the load upon the engine or other 75 operating mechanism.

It will thus be seen that I have provided a very highly novel, simple and efficient form of attachments for the pumps of the character shown, that will tend to equalize the 80 load on the engine or other power means during the up and down stroke of the piston, resulting in the efficient operation of the same, preventing jarring of the pump parts and consequently prolonging the life of the 85 pump mechanism.

Springs of various tension may be provided to meet the load requirements and other changes may be made in the invention without departing from the spirit and scope 90 of the appended claims.

Having thus described my invention, what I claim as new and desire to secure by Letters Patent is:—

1. In an attachment for pumps of the 95 type including a stock through which projects a piston rod that is operatively connected at its projecting end with pitmen at the opposite sides of the stock, which are in turn connected at their lower ends to the operating mechanism of the pump, a cross bar through which the upper portion of the piston rod is slid able, and contractile coil springs connected to the opposite ends of the cross bar, and the pitmen respectively for assisting in the upward movement of the 100 pitmen.

2. In combination with a pump mechanism including a stock through which is 105 movable a piston rod, operating mechanism 110

for the pump including pitmen rods at the opposite sides of the stock, a connection between the upper end of the piston rod and the upper ends of the pitman rods, the lower ends of the pitman rods being operatively associated with the pump actuating mechanism, a member through which the upper

portion of the piston rod is slidable, and an elastic connection between the lower portion of each of the pitman rods, and the respective side of said member for assisting in the upward movement of the pitman rods. 10

In testimony whereof I affix my signature.

WILLIAM G. BRUNS.
